PROCESS OF DEWAXING HYDROCARBON OILS

Paul D. Barton, Scarsdale, N. Y., assignor, by
mesne assignments, to Sun Oil Company, Phil-
adelphia, Pa., a corporation of New Jersey

Application January 22, 1934, Serial No. 707,637

5 Claims. (Cl. 196—18)

My invention relates to a dewaxing process and more particularly to a multi-stage dewaxing process utilizing an excess of a solvent diluent in the first stage.

Generally speaking, in a process for dewaxing hydrocarbon oils containing a large percentage of paraffin wax which utilizes a normally gaseous liquified hydrocarbon solvent such as propane to secure dilution, chilling and resultant crystallization of the wax, considerable difficulty has been experienced in transferring through pumps, pipe lines and other pieces of equipment associated with the process, the wax-bearing oil diluted in the customary manner. The viscosity of oil solvent mixture under the usual dilution conditions of, for example, one part oil and three parts propane is such as to preclude a satisfactory commercial rate of dewaxing in a continuous process.

It is an object of my invention to provide a process for dewaxing hydrocarbon oils containing a high percentage of wax not readily removed by a continuous process involving low dilution of the oil with a hydrocarbon solvent because of mechanical difficulties incident to pumping and filtration.

Another object of my invention is to provide a multi-stage dewaxing process in which a hydrocarbon oil bearing a high percentage of wax is highly diluted with a hydrocarbon solvent, chilled and partially dewaxed, the concentration of the partially dewaxed oil in the solvent then being increased by denuding the mixture of some solvent, the oil again chilled to a lower wax precipitating temperature and additional wax removed to give the desired low cold test oil.

Other and further objects of my invention will be seen from the following description.

The accompanying drawing which forms part of the instant specification and is to be read in conjunction therewith is a schematic drawing of one form of apparatus capable of carrying out the process of my invention.

In general, I mix a stock bearing a high percentage of wax with a liquified, normally gaseous hydrocarbon solvent such as propane, for example, under such conditions as will secure an initial dilution sufficient to obtain a solution and permit more ready transfer of the solution to a second mixing chamber where a large amount of solvent diluent which has been separately chilled to a predetermined low wax precipitating temperature is mixed with the first oil diluent solution. This highly diluted and chilled solution is held under pressure in a separating tank which permits a preliminary settling of the larger and heavier

wax crystals solidified and from which separator a selected upper portion of the oil from which some of the wax has been crystallized and precipitated by the chilled solvent, is removed, filtered, and then completely or partially denuded of the solvent diluent before subsequent further dewaxing. The removal of a predetermined amount of the solvent at this point is necessary before further dewaxing is attempted in order that the proper concentration of the oil in the diluent for most favorable wax crystallization conditions may be secured. It may be desirable as an alternative to remove all of the initial solvent at this point and utilize a different solvent of higher vapor pressure for the subsequent further dewaxing operation. The remaining oil wax slurry from the separating tank is passed through filters, the filtrate from which is combined with the partially dewaxed undenuded oil while the slurry from the filters is denuded of this propane solvent and passed to storage as first wax or petrolatum.

The partially dewaxed oil with solvent diluent for the desired concentration, is cooled by indirect heat exchange from surrounding evaporating propane and passed into a crystallizer tank where evaporation is prevented by pressure of a lighter gas and where the time, temperature conditions necessary for crystallization are maintained. This process of chilling and crystallizing under pressure is carried on through a number of steps, the temperature and pressure decreasing and the amount of crystallized wax increasing in each step. The final desired crystal formation is achieved in the last crystallizer where the diluent is caused to evaporate either from direct pressure relief or as the result of a light gas partial pressure effect to secure the proper oil concentration in the solvent. Some temperature reduction may occur as the result of incidental auto-refrigeration in the last crystallizer though indirect heat exchange may be used. The oil, bearing the crystallized wax, is then passed through a series of filters of desired type, the filtrate of dewaxed oil being taken off, denuded of diluent in a distillation zone, and then sent to storage as finished dewaxed oil of the desired low cold test. The slurry from the filters is collected and pumped to a distillation zone for the removal of the diluent, the denuded material being sent to storage as the second wax or petrolatum.

It is to be noted that I maintain the pressure on the initial separating tank sufficient to prevent evaporation of the propane attendant in the initial oil propane solution, thus inhibiting auto-

refrigeration by evaporation of a part of the diluent. The gas serving as a pressure medium on this settling tank and on the crystallizers in the second stage of crystallization is selected from a gas having relatively low solubility in the oil-propane mixture. This gas may be, for example, carbon dioxide or methane. The latter is especially desirable for securing propane evaporation by partial pressure reduction in the later crystallizers.

Referring now more particularly to the drawing, a wax-bearing stock from tank 1 is pumped through a line 2 by pump 3 to a mixing chamber 4 where it is mixed with a normally gaseous liquefied hydrocarbon solvent diluent such as propane or the like, taken from tank 5 and pumped through the line 6 by pump 7. The oil diluent solution is transferred through the line 8 to a second mixing chamber 9. Diluent is withdrawn from the tank 5 through the line 10 and injected into the chiller 11 where it is cooled as a result of evaporation of a portion of the diluent, the gas escaping through line 12 having a pressure relief valve 13. The chilled diluent from the chiller 11 is pumped through a line 14 having a pump 15 to the mixing chamber 9. The highly diluted oil diluent solution from the chamber 9 passes through the line 16 to a separating tank 17 having a series of baffle plates 18 arranged to minimize agitation resulting from eddy currents set up in the tank.

A compressor 19 serves to pump a light gas such as carbon dioxide or methane to tank 19a, fitted with drain 19b. Gas from tank 19a passes through the line 20 and branch line 21 to the separating tank 17 at a pressure sufficient to prevent evaporation of the diluent in the tank. As a result of the interchange of sensible heat between the oil and subcooled diluent, some of the wax in the oil is crystallized, settles and increases the percentage of wax crystals in the lower portion of the oil solution in tank 17. A layer of partially dewaxed oil is withdrawn from the upper level of the tank through the line 22 and injected into a filter unit of the desired type as 23. A filtrate of partially dewaxed oil is withdrawn from the filter unit 23 through line 24 connected to a filtrate main 25 passing to an accumulator tank 26. The oil wax slurry in the lower portion of the filter unit 23 is withdrawn through the line 27 and combines with oil wax slurry being withdrawn from the tank 17 through the line 28. This slurry is passed through the line 29 to the filter unit 30 from which filtrate may be withdrawn through the line 31 and slurry through the line 32. The slurry is further filtered in the filter unit 33, filtrate being withdrawn through the line 34 and slurry through the line 35. The filtrate being withdrawn from the units 30 through the lines 31 and 34 is passed into the main 25 connecting with the accumulator tank 26. Valves 36 and 37 are provided in the line 28 permitting the units 30 and 33 to be operated in series or cut out as desired.

The partially dewaxed oil is withdrawn from the tank 26 through the line 38 having a pump 39, passed through the heat exchanger 40 to a distillation unit 41 where the diluent is wholly or partially distilled off and collected in the main 42. The partially dewaxed oil denuded of its diluent is then sent through the line 43 to a tank 44. Alternatively, the partially denuded oil may be introduced directly to the first indirect solution chiller 54 through a by pass 43a, controlled by valve 43b. The wax slurry from the filter

unit 33 is withdrawn through the line 35 connecting to the line 45 which passes to a distillation unit 46 serving to remove the diluent which passes off through the line 42 while the denuded wax or petrolatum passes off through the line 47 to storage.

The partially dewaxed oil is passed to a mixing chamber 50, either from tank 44 or through line 43a. Diluent which may be the same or have a higher vapor pressure is withdrawn from the tank 5 (or a separate tank, not shown) through the line 51 having a pump 52 and mixed with the oil in the mixing chamber 50 in the desired ratio to give the required higher oil concentration for low cold test oil product. The oil diluent mixture passes through line 53 and heat exchanger 54, to the crystallizer 55. The oil withdrawn from the crystallizer 55 passes through lines 53 and a series of heat exchangers 54a, 54b, 54c, and crystallizers 55a, 55b, 55c arranged in series. Liquid diluent is introduced to each of the heat exchangers 54 through the lines 56, permitted to evaporate and escape through the lines 57 having pressure relief valves 58. These lines are connected to a main 59 running to the inlet side of the pump of the compressor 60 to the outlet of which is connected a line 61 passing through heat exchanger 62 to the diluent supply tank 5. Pressure is maintained on each of the crystallizers 55 by compressed light gas injected through the lines 63. Branch lines may be provided for injecting light gas directly into the oil diluent solution if desired to secure diluent evaporation by partial pressure effect in the last crystallizer. A series of escape lines 64 provided with pressure relief valves 65 are connected to a common main 66 which returns the gaseous diluent to the intake side of the compressor 19.

Each of the crystallizers 55, 55a, 55b, 55c, is provided with liquid level controls 91, 92, 93, 40 94, respectively, for operating the valves 98, 98a, 98b, 98c, respectively, for controlling the pressure and flow of the liquid into the respective crystallizers 55, 55a, 55b, and 55c.

The oil bearing the crystallized wax is withdrawn from the last crystallizer 55c through the line 67 having a pump 68. Branch lines 69, 70, 71 and 72 connect the line 67 with the filter units 73, 74, 75 and 76. Withdrawal lines 77, 78, 79 and 80 connect the bottom of the filter units with the line 67 which is also provided with the valves 81, 82, 83 and 84 which permit the filter units to be operated either in series or cut out as desired. The filtrate from the filter units is removed through the line 85 and passed into a distillation unit 86 from which the diluent is removed through the lines 86a and 42, and the finished dewaxed oil removed through the line 87. It will be understood that if a different diluent from that in tank 5 is used, line 86a will return the same to its own tank (not shown). The wax-diluent slurry from the filter unit is passed through the line 88a to the tank 88 from which it is removed through a line 89 having a pump 90 and sent to a distillation unit 91 from which the diluent is removed through the line 42 and the wax or petrolatum removed through the line 92. The accumulated diluent from the distillation units 41, 46, 91 and 86 may be collected in the line 42 and passed through a branch line 93, cooled in heat exchanger 94, to an accumulator 95 from which it is returned through the line 96 and heat exchanger 40 to the diluent supply tank 5.

One example of the operation of my process is as follows:

The wax-bearing stock and diluent such as propane from tanks 1 and 5 respectively are combined in the mixing chamber 4 in ratio of about one to three parts by volume. This solution, as a result of sensible heat exchange (and the operation of an external water cooled heat exchange means, if desired, (not shown) will be cooled to a temperature of about 75° F. Diluent withdrawn from the tank 5 is sub-cooled to 10 —45° F., for example, in the chiller 11 by evaporation of a portion thereof, the sub-cooled diluent then being mixed with the first oil diluent solution in the chamber 9 in a ratio of two to twenty, for example. The entire solution 15 now reaches a temperature of about —30° F. in the separating chamber 17 where the diluent is kept from evaporating as a result of the restraining action of the carbon dioxide or methane at a pressure which may be as high as 200# 20 maintained by the compressor 18 on the separating tank 17. There will be a slight rise in temperature of the filtrate from the filter units 23, 30 and 33, the partially dewaxed oil in the accumulator 26 being, for example, in the neighborhood of —25° F. This oil, after passage 25 under pressure through the heat exchanger 40 and distillation unit 41, will be at a temperature governed by available cooling water, say about 80° F. and at a pressure in the neighborhood 30 of 175#. The oil is either completely denuded of diluent in distillation unit 41 and then accumulated prior to redilution with a diluent of higher vapor pressure, or sufficient diluent is removed to secure a concentration of the oil-diluent ratio 35 which will insure proper crystal growth in the subsequent dewaxing step.

The oil, if completely denuded of diluent is withdrawn from the accumulator 44 and mixed with a different diluent from the tank 5 or a separate tank (not shown) in a ratio of substantially one part oil to three parts of diluent by volume. The temperature of the mixture will be around 70° F. and this will be cooled in passing through the indirect solution cooler 54₁ to a temperature of +30 F. as a result of the evaporation of diluent in the indirect solution cooler 54₁, which diluent will be at a temperature of from 0 to —15° F. The wax oil solution from the first crystallizer 55, will be cooled in passing through the second indirect solution cooler 54₂ to a temperature of 0° F., in passing through the third indirect solution cooler 54₃ to a temperature of —10° F., and in passing through the fourth solution cooler 54₄ to a temperature of —20° F. Each of the crystallizers 55 is maintained under pressure by the gas from tank 19a to prevent evaporation of the diluent in the crystallizers. This pressure may be less in each crystallizer due to the progressively decreasing temperature of the mixtures. For example, the first crystallizer 55₁ may be at 200# pressure, the second 55₂ at 150# pressure and the third 55₃ at 100# pressure. The fourth crystallizer 55₄ will be at atmospheric pressure and diluent will be permitted to evaporate from the mixture either by the reduction to atmospheric pressure or as the result of injected light gas to secure the desired concentration of mother liquor giving favorable crystal growth. The oil-wax diluent mixture removed from the last crystallizer 55 is filtered in the selected filter units, the filtrate removed through line 85 being denuded of its diluent in the distillation unit 86 and sent to storage as finished dewaxed oil through the line 87. The slurry from units 13-16 is accumulated

in tank 88 and pumped through line 89 to distillation unit 91 where the diluent is removed. The petrolatum is sent to storage through line 92.

It will be understood that certain features and subcombinations are of utility and may be employed with reference to other features and subcombinations. This is contemplated by and is within the scope of my claims. It is further obvious that various changes may be made in details within the scope of my claims without departing from the spirit of my invention. It is, therefore, to be understood that my invention is not to be limited to the specific details shown and described.

Having thus described my invention, what I claim is:

1. A process for dewaxing hydrocarbon oils comprising diluting the oil with a hydrocarbon solvent, chilling the oil-diluent solution to secure partial crystallization of the wax, separating the wax from the oil, denuding the partially dewaxed oil of the solvent, diluting the partially dewaxed oil with a different hydrocarbon solvent of higher vapor pressure than said first solvent, chilling the oil-diluent solution to crystallize a further portion of the wax and removing the wax from the oil.

2. A process for dewaxing hydrocarbon oils comprising diluting the oil with a hydrocarbon solvent, further diluting the oil-solvent solution with a chilled hydrocarbon solvent to secure crystallization of a portion of the contained wax, separating the wax from a selected portion of the oil, denuding the partially dewaxed oil of the hydrocarbon solvent, diluting the partially dewaxed oil with a different hydrocarbon solvent of higher vapor pressure than said first solvent, chilling the oil-diluent solution to a temperature lower than that achieved in the first stage of dewaxing and removing the wax from the oil.

3. A process for dewaxing hydrocarbon oils comprising diluting the oil with a solvent diluent, chilling a solvent diluent by auto-refrigeration, further diluting the oil-diluent solution with the chilled diluent, introducing the highly diluted chilled solution to a separating stage, maintaining a pressure in the separating stage with a gas substantially insoluble in the solution sufficient to prevent evaporation of the diluent, removing a selected portion of solution from the separating stage and introducing it to a filtering stage, removing the filtrate and partially denuding it of the solvent diluent in a distillation stage, to secure a much higher oil concentration in the solution, progressively chilling the solution and crystallizing the wax in a series of heat exchange and time crystallization stages while maintaining a super atmospheric pressure in the crystallizing stages with a gas substantially insoluble in the solution, evaporating the diluent from the mixture in the last stage of crystallization to secure the desired concentration of oil, removing the mixture from the crystallizer and introducing it to a filtration stage, removing the filtrate and denuding the wax free oil of the diluent in a distillation stage.

4. The process of claim 3 in which the first oil-diluent solution is in substantially the ratio of one to three parts by volume, in which the second oil-diluent solution is in the ratio of substantially two to twenty parts by volume and in which the partially denuded oil-diluent solution is in the ratio of substantially one to three parts by volume.

5. A process of dewaxing hydrocarbon oils

comprising preparing a highly diluted oil solvent solution, chilling the solution, filtering the solution to secure a partially dewaxed oil diluent filtrate, removing a portion of the diluent from the filtrate, chilling the filtrate diluent solution to a predetermined temperature lower than said first chilling temperature by indirect heat exchange while maintaining a super at-

mospheric pressure on the solution, then evaporating a portion of the diluent to secure a predetermined oil to solvent ratio higher than in said first solution and the final desired crystal formation, and removing the wax from the mixture.

PAUL D. BARTON.
